RADIO INTERFERENCE ELIMINATOR FOR
ELECTRICAL APPLIANCESHarry L. Collins, Dover, Ohio, assignor to The
Hoover Company, North Canton, Ohio, a cor-
poration of Ohio

Application December 24, 1936, Serial No. 117,461

4 Claims. (Cl. 171—252)

This application relates to application of radio interference eliminating condensers to portable motor-driven household appliances and more particularly to small suction cleaners for the purpose of eliminating, or at least minimizing, the interference to clear reception due to the operation of the motor in the vicinity of the radio-receiving set.

Without going into the electrical phenomena associated with radio reception interference, it will suffice to say that it is possible by means of a condenser in the motor circuit to eliminate the causes of radio interference. Nor is it necessary to explain the nature of a condenser, except to point out that it is an electrical device or apparatus that has a definite capacity for accumulating electrical charges. In short, the present invention does not pertain to the problem of radio interference elimination nor to the design of a suitable condenser for this purpose, but rather to the problem of incorporating the condenser in the appliance.

And inasmuch as the electrical appliance of the present disclosure is a small portable suction cleaner having a handle fixed to the body of the appliance, a further object of the present invention is to provide an arrangement for mounting a condenser within the hollow grip portion of the handle, and as shown in the accompanying drawings, in which—

Figure 1 is a general view in side elevation of a small portable suction cleaner with portions broken away to show the general design of the cleaner and the mounting for a condenser within the handle.

Figure 2 is an enlarged top plan view of the handle, with a portion of the cover plate broken away to show the condenser mounting.

Figure 3 is a detail view in side elevation of the handle and adjacent portion of the cleaner casing, said handle being shown for the most part in vertical section as taken on line 3—3 of Figure 2, and a portion of the cleaner casing broken away to show the motor mounting.

Figure 4 is an enlarged fragmentary view showing a modified handle construction and condenser mounting in top plan view, with a portion of the cover plate broken away to show the interior of the handle.

Figure 5 is a view in side elevation of the handle and adjacent portion of the cleaner casing, with portions thereof shown in vertical section as taken on line 5—5 of Figure 4.

Figure 6 is a detail view in cross section

through the handle as taken on line 6—6 of Figure 5, and

Figure 7 is a wiring diagram of the electrical circuit of the motor showing the location of the condenser therein.

Referring first to the appliance to be equipped with a radio interference eliminating condenser, the same comprises a light portable suction cleaner of the type that is held by the operator in one hand as it is moved over the surface to be cleaned and intended primarily for cleaning upholstered and fabric surfaces other than carpets and rugs. As such, the cleaner comprises a cylindric shaped casing 1, having a down-turned nozzle portion 2 at its forward end and a dirt bag 3 removably attached at its opposite end. Within the casing 1 is a motor 4 driving a suction fan 5 mounted directly upon the forward end of the motor armature shaft. The motor 4 is of any standard type and design consisting of the usual arrangement of armature, field core and commutator all enclosed within a sheet metal frame or housing 4a. As a preferable arrangement the motor is supported within the casing 1 through the medium of rubber spacing blocks 6, so that the entire motor is insulated from the rest of the cleaner.

Mounted on top of the cleaner casing is a U-shaped handle 7 preferably molded from a suitable plastic substance, and having an upwardly opening cavity formed therein and extending substantially the length and depth of the longitudinal grip portion thereof, as clearly shown in Figure 3. Entering the cavity at the rear end of the handle is a conductor cord 8 for supplying current to the motor, this cord having suitable anchorage in the rear end of the handle as is customary in electrical appliances of this character.

For the purpose of the present disclosure it is not deemed necessary to identify each element of the motor circuit as the same is comparatively simple and is fully understandable from the wiring diagram of Figure 7, in which the various parts of the circuit are represented by the usual electrical symbols.

Thus resorting to letters instead of numerals to designate the electrical elements of the circuit, the current supply line carried by the cord 8 leads first to a switch 8 located at the forward end of the handle cavity, and preferably supported by a cover plate 9 which seats over the top opening of the cavity and is held in place by means of screws 9a, 9a. The switch may be of any standard type suitable for the purpose, the

one shown herein having a switch lever of the rocking snap type operated by the thumb to open or close the circuit. The switch S is located in one of the conductors leading to the motor (M on the wiring diagram) and across the line immediately beyond the switch is the interference eliminating condenser C which is grounded on the frame of the motor.

The condenser C consists electrically of a group of positive and negative plates insulated from each other and forming a small compact unit of a flattened cylindric shape. The condenser is necessarily small in size and fits snugly within the handle cavity adjacent its rear end. Moreover the condenser is located just beneath the cover plate 9 being covered by a shield 10 consisting of a thin sheet of insulating material bent into U-shape and inserted into the cavity with its open side downwardly, the shield being somewhat longer than the condenser so as to afford protection to the wires which lead into the condenser from each end. And finally, the condenser with its protecting shield 10 lies along the upper edge of the handle cavity thus leaving sufficient space below for the wiring leading inwardly through the rear end of the handle.

The arrangement shown in Figures 4, 5 and 6 is a modification of that shown in Figures 1 to 3 inclusive, the essential departure being in the formation of the handle and the location of the condenser. Thus the handle 12 is preferably molded of a suitable plastic substance and in two halves permanently joined together by means of double-ended drive screws 13. Otherwise the formation of the handle is substantially the same as before, having a cavity opening along the top edge of the handle and closed by a cover plate 14. The switch S and the various wires leading to and from the motor are located within the cavity as is also the condenser C, although its location and method of mounting is somewhat different. Extending along the bottom of the cavity and substantially throughout one-half its length, is a relatively shallow recess 15 closed at its forward end by means of an upstanding transverse wall segment 16. This recess 15 is sufficiently large to receive the condenser C which lies lengthwise therein with sufficient space at either end to accommodate the wires leading thereto. And finally, the condenser is preferably embedded in a mass of insulating material 17 which is preferably introduced into the recess and around the condenser in molten form, becoming solid after it has cooled. Thus, except for the change in the location of the condenser within the handle cavity and the method of insulating it from the other current carrying elements, the two arrangements herein disclosed are sub-

stantially the same and have the common attribute of compactly locating the condenser within the hollow handle of an electrical appliance.

Having therefore set forth alternative methods of accomplishing the advantageous features of the disclosure, I claim:

1. In a motor driven electrical appliance of the character described, the combination of a casing, a motor housed within said casing, a handle rigidly attached to the exterior of said casing and provided with an externally accessible cavity, a switch mounted in said cavity, a current supply line leading into said cavity to said switch and thence to said motor, a condenser mounted in said cavity and electrically connected across said supply line and an insulator surrounding said condenser and holding it against displacement within said handle cavity.

2. In a motor driven electrical appliance of the character described, the combination of a casing, a motor housed within said casing, a handle rigidly mounted on said casing and provided with an externally accessible cavity, a switch carried by said handle and mounted in said cavity, electrical conductors leading into said cavity from one end of said handle and to said motor through said switch, and a condenser electrically connected in circuit with said conductors and fitting within said handle cavity separated from the adjacent surfaces thereof by a shield of insulating material.

3. In a motor driven electrical appliance of the character described, the combination of a casing, a motor housed within said casing, a handle rigidly attached to the exterior of said casing and provided with an externally accessible cavity, a switch carried by said handle and mounted in said cavity, electrical conductors leading into said cavity from one end of said handle, the current supplied by said conductors being controlled by said switch, and a condenser located within a recess at the bottom of said handle cavity and embedded in a mass of insulating material.

4. In a motor-driven electrical appliance of the character described, the combination of a casing, a motor mounted in said casing, a handle attached to said casing and provided with an externally accessible cavity, electrical conductors leading into said cavity and thence to said motor, a switch and a condenser located in said cavity and in circuit with said conductors, and means for insulating said condenser from said switch and electrical conductors within said cavity and for holding the same against displacement therein.

HARRY L. COLLINS.
